TOY

Harry D. Adams, Brookline, Mass.

Application April 3, 1939, Serial No. 265,619

5 Claims. (Cl. 46—152)

The invention relates to an improvement in toys imitative of snakes, or other objects having sinuosity of movement.

The essential object of the invention is to provide a construction by which a sinuous movement may be imparted to the object with a minimum of frictional resistance, for in frictional resistance resides the essential difficulty to be overcome.

10 A further object is to provide a construction which may be operated or driven by mechanism residing in the object itself, and which may be actuated by a contained spring.

The invention can best be seen and understood by reference to the drawing in which the invention is shown applied to an object in simulation of a snake.

Fig. 1 is a plan view of the object.

Fig. 2 is a horizontal cross section thereof longitudinally the object on the line 2—2 of Fig. 1.

Fig. 3 is a cross section thereof on the line 3—3 of Fig. 1.

Fig. 4 is a side elevation of one of the elements later to be referred to.

Fig. 5 is a cross section of the element on the line 5—5 of Fig. 4.

Fig. 6 is a plan of another of the elements later to be referred to.

Fig. 7 is an end elevation of the element shown in Fig. 6.

Fig. 8 is a side elevation of a modified type of element later to be referred to.

Fig. 9 is an end elevation of the element shown in Fig. 8; and

Fig. 10 is a plan of the head of the object with the top section thereof removed to show the mechanism within the head.

Fig. 11 is a side elevation of an elemental part of the actuating mechanism.

40 Referring to the drawing: 1 represents the body of the snake, 2 the tip at the tail end, and 3 the head. The body of the snake is made up of a plurality of segments 4 fashioned in manner to collectively give form to the snake. The segments may be made of any suitable material possessing especially the qualities of lightness and smoothness of surface that will impart as little frictional resistance as possible. The segments may be made of wood, but preferably 45 from some composition material which may be formed by molding, or stamping. The tip 2 at the tail end of the snake may be made out of the same material as the body segments, but is made more or less elongated, and narrowing to 50 a point at the extreme tip end. The head is

made in separable sections 5 and 6, stamped or otherwise formed out of thin metal plate. The head is preferably made relatively large for within it is located the mechanism which operates, or furnishes the power for imparting sinuosity to, the snake. The mechanism is supported by a frame 8 located within the head and affixed to the lower section 6 thereof in any suitable manner, as by tongues 9 on the frame passed through the metal of the section on which the 10 frame is resting, and clinched beneath it.

The ends of the body segments 4 are convexed and concaved, respectively, the concavity to the end of each segment describing an arc of a circle whose radius is preferably substantially 15 equal to the length of the segment. The convex surface of each body segment has the same relative arc so that when the segments are brought together the joint 10 between their meeting edges will describe said arc, thus enabling the segments to turn on each other, or relatively to each other. The end of the tip 2 is convexed in the same manner as the other segments in order that the concaved end of the body segment adjacent to it may have arcuate 20 connection with the tip.

All the segments 4, not including the tip 2, are cored to form continuous slots 11, 12 through them, within which are contained separate elements 13, 14. Of these the element 13, contained in the slot 11, acts to hold the segments together in proper operative relationship to one another and permit of sinuosity being imparted to the object. The other element 14, contained in the slot 12, is a driven element for imparting 25 such sinuosity. The slot 11 is a relatively narrow but vertically deep slot, although its vertical depth may vary, depending upon the size of the element 13 contained within it, which is narrowed as approach is made to the tail end 40 of the object where the body segments are diminished in size. The element 13 comprises a strip of any suitable material which will possess the quality of easy lateral flexibility without extensibility. In practice there is employed a 45 relatively thin strip of vulcanized fibre, or of some cellulosic material, preferably perforated throughout, to increase its flexibility. The strip is made of such width that it will, when vertically set on edge, about fill the slot 11 through the segments, but with a loose fit therein in order that the segments while supported thereby lie floatingly supported thereon, with freedom to move in relation to each other so as to be easily movable in the plane in which they are lying. 50 55

with the least possible friction. The ends of the strip are fixed, one end being fixed to the tip 2 and the other end to the head and this preferably by fixing it to the end segment adjacent to the head which is fixed to the head as will later be explained. With the strip thus retained the segments become loosely threaded thereon and floatingly supported thereby as aforesaid. The strip also acts to prevent the segments turning relatively to one another, the segments being retained to lie in their original plane although their positions may be changed in this plane as sinuosity is imparted to the object. During the impartation of such sinuosity the segments will move, or assume changed relative positions on the strip, by sliding thereon and by turning laterally on each other, the convexed end of one segment turning within the concaved end of the next adjacent segment, thus obtaining high flexibility, with as little friction as possible.

The slot 12 through the segments, in which is contained the element 14 which imparts sinuosity to the object, is a relatively narrow slot, although of sufficient width to loosely contain the element 14 which consists of a metal rod, or wire, of generally sinusoidal or helicoidal form and of such appreciable size as will enable it to retain its shape without flexing when rotated within the slot 12. In depth, or vertical height, the slot 12 is made as deep as the size of the segments will permit, in order to receive an element 14 that may rotate without flexing within the slot and describe when turned as large a circle as possible, for upon the size of this circle will depend the extent to which sinuosity can be imparted to the object. Necessarily the circle within which the element 14 may turn will vary according to the size of the segments within which the slots 12 are made. Where the segments are made smaller, and the slots 12 of less vertical depth, the element, or rod, 14 will necessarily be formed to turn within a smaller circle than do other parts of the rod which turn within a larger circle where the segments are made larger and the slots 12 therein of increased vertical depth. In any event, the circle described by any part of the rod as the rod is turned should not be greater in its outside diameter than the vertical depth of the slot within which said any part of the rod is turning.

The element, or rod, 14 has ends 15 and 16, respectively. Between these ends the rod is preferably made in the form of an elongated helix, as shown in Fig. 6. It might be made, also, with single plane sinuosity, as shown in Fig. 8. Of the ends 15 and 16 of the rod, the end 15 extends through the back of the frame 3 located in the head, and through a bearing 18 on this frame. The inner end of the rod accordingly is arranged to turn within the head 3 in separate spaced bearings. The opposite end 16 of the rod is socketed to turn within the tip 2 at the tail end of the object. The ends 15 and 16 lie within the axis around which the rod 14 turns, and as the rod, made helicoidal, or sinuous, as aforesaid, is turned within the slots 12 in which it lies the body segments 14 of the object will accordingly be displaced by the rod to the right or left by the bearing of the rod against the interior side walls of the sockets within the segments whereby adjacent groups of segments will be displaced laterally in opposite directions relative to each other, thus imparting sinuosity to the object. The helicoidal or sinuous form of the rod should be so elongated that

its bearing against the body segments will be a gradual and easy bearing in order to eliminate frictional resistance as much as possible. As the segments become thus displaced they will move upon the element, or strip, 13 upon which they are floatingly supported. They will also turn upon each other, the end one of the body segments turning upon the tail piece. These movements take place with little frictional resistance owing to the manner in which the body segments are mounted upon the strip 13, and the arced jointure between them.

The rod 14 is turned by a driving mechanism 20 located within the head, and which imparts its power to a face gear 21 on the end of the rod 14. The driving mechanism 20 includes a coiled spring 22 arranged upon a winding shaft 23 which aligns an opening 24 in the side of the head, and is wound by means of a key. The driving mechanism includes, also, an escapement 25 co-operating with a star wheel 26 for preventing retraction of the spring when wound. The escapement is provided with a finger release 25' which projects through an opening 27 in the head. While sinuosity of movement is imparted to the object by the mechanism thus far described, the object is rendered movable in a longitudinal direction, or made to travel, by means of a set of wheels 28 fixed to a shaft 29 and projecting through the under side of the head. The traction afforded by these wheels with the floor, or other surface on which the object is placed, enables it to travel over such surface.

The two sections 5 and 6 of the head have preferably a snap fastening engagement with one another which enables them to be combined, or the top section removed on undoing the fastening. To this end the top section 5 at the lip end thereof is provided with a tongue 30 which enters to interlock with a slot 31 in the lip end of the bottom section 6. The top section turns on this tongue. As the top section is brought down the sides of the bottom section are sprung inwardly to permit the sides of the top section slipping over them, and engagement is then made between the sides of the two sections then overlapping by tongue 32 on the top section entering slots 33 in the bottom section. To release the top section and permit of its removal the bottom section can be pinched sufficiently to disengage the slots 33 therein from the tongues 32 on the top section, when the top section may be lifted and removed.

A further advantage of this construction for uniting the two head sections resides in the fact that when the sides of the bottom section are contracted, and held contracted by the interlocking engagement of the top section as aforesaid, the sides of the bottom section will grip and hold the foremost one of the body segments 4 of the object which slips into a neck extension 34 to the bottom section, and when its sides are contracted the sides of the extension will grip and hold the segment, thus obtaining a finished connection between the body segments of the object and the head.

Two of the strips 13 upon which the segments are floatingly arranged are preferably employed, as better balance is imparted thereby to the device during the operation thereof.

While it is described that the end of the element or rod, 14 is socketed to turn within the tip 2 at the tail end of the object, and which is a construction more to be desired, yet this may be

dispensed with and a good result will be obtained in the animation of the object, inasmuch as the rod is retained within the head at points of separate bearings well spaced from one another, thereby maintaining the rod to turn around its axis for effecting displacement in opposite directions of groups of body segments, as previously explained.

I claim:

1. A toy imitative of an object having sinuosity of movement, comprising head and tail ends and a body comprising a plurality of assembled segments having a plurality of relatively narrow but vertically deep slots extending, respectively, continuously through them, a laterally flexible substantially inextensible strip fixed to extend edgewise through one of said slots in said body and upon which strip said segments in loose assembly are floatingly arranged, a rod extending through another of said slots in said body with ends retained to turn within said head and tail ends, respectively, that portion of the rod extending through the slots in said body being formed to describe when turned a generally sinusoidal curve whereby adjacent groups of said body segments will be displaced laterally in opposite directions relative to each other and sinuosity be thereby imparted to the toy as the rod is turned, said rod being substantially inflexible during the turning thereof and turning within circles of which the circle described by any part of the rod as the rod is turned is not greater in its outside diameter than the vertical depth of the slot within which said any part of the rod is turning, and means for turning said rod.

2. A toy imitative of an object having sinuosity of movement, comprising head and tail ends and a body comprising a plurality of assembled segments, the ends of which are concaved and convexed, respectively, and which segments have, also, a plurality of relatively narrow but vertically deep slots extending, respectively, continuously through them, a laterally flexible substantially inextensible strip fixed to extend edgewise through one of said slots in said body and upon which strip said segments in loose assembly are floatingly arranged, a rod extending through another of said slots in said body with end retained to turn within said head, that portion of the rod extending through the slots in said body being formed to describe when turned a generally sinusoidal curve whereby adjacent groups of said body segments will be displaced laterally in opposite directions relative to each other and sinuosity be thereby imparted to the toy as the rod is turned, said rod being substantially inflexible during the turning thereof and turning within circles of which the circle described by any part of the rod as the rod is turned is not greater in its outside diameter than the vertical depth of the slot within which said any part of the rod is turning, and means for turning said rod.

3. A toy imitative of an object having sinuosity of movement, comprising head and tail ends and a body comprising a plurality of assembled segments, the ends of which are concaved and convexed, respectively, and which segments have, also, a plurality of relatively narrow but vertically deep slots extending, respectively, continuously through them, a laterally flexible substantially inextensible strip fixed to extend edgewise through one of said slots in said body and upon which strip said segments in loose assembly are floatingly arranged, a rod extending through another of said slots in said body with ends retained to turn within said head and tail ends, respectively, that portion of the rod extending through the slots in said body being formed to describe when turned a generally sinusoidal curve whereby adjacent groups of said body segments will be displaced laterally in opposite directions relative to each other and sinuosity be thereby imparted to the toy as the rod is turned, said rod being substantially inflexible during the turning thereof and turning within circles of which the circle described by any part of the rod as the rod is turned is not greater in its outside diameter than the vertical depth of the slot within which said any part of the rod is turning, and means for turning said rod.

4. A toy imitative of an object having sinuosity of movement, comprising a head and a body comprising a plurality of assembled segments, the ends of which are concaved and convexed, respectively, and which segments have, also, a plurality of relatively narrow but vertically deep slots extending, respectively, continuously through them, a laterally flexible substantially inextensible strip fixed to extend edgewise through one of said slots in said body and upon which strip said segments in loose assembly are floatingly arranged, a rod extending through another of said slots in said body with end retained to turn within said head, that portion of the rod extending through the slots in said body being formed to describe when turned a generally sinusoidal curve whereby adjacent groups of said body segments will be displaced laterally in opposite directions relative to each other and sinuosity be thereby imparted to the toy as the rod is turned, said rod being substantially inflexible during the turning thereof and turning within circles of which the circle described by any part of the rod as the rod is turned is not greater in its outside diameter than the vertical depth of the slot within which said any part of the rod is turning, and means for turning said rod.

5. A toy imitative of an object having sinuosity of movement, comprising a head and a body comprising a plurality of assembled segments having a plurality of relatively narrow but vertically deep slots extending, respectively, continuously through them, a laterally flexible substantially inextensible strip fixed to extend edgewise through one of said slots in said body and upon which strip said segments in loose assembly are floatingly arranged, a rod extending through another of said slots in said body with end retained to turn within said head, that portion of the rod extending through the slots in said body being formed to describe when turned a generally sinusoidal curve whereby adjacent groups of said body segments will be displaced laterally in opposite directions relative to each other and sinuosity be thereby imparted to the toy as the rod is turned, said rod being substantially inflexible during the turning thereof and turning within circles of which the circle described by any part of the rod as the rod is turned is not greater in its outside diameter than the vertical depth of the slot within which said any part of the rod is turning, and means for turning said rod.

6. A toy imitative of an object having sinuosity of movement, comprising a head and a body comprising a plurality of assembled segments having a plurality of relatively narrow but vertically deep slots extending, respectively, continuously through them, a laterally flexible substantially inextensible strip fixed to extend edgewise through one of said slots in said body and upon which strip said segments in loose assembly
